CONTINUOUS WIRE MILL

Josef Gassen, Dusseldorf, Germany, assignor to
Schloemann Aktiengesellschaft, Dusseldorf,
Germany, a corporation of Germany

Application August 22, 1932, Serial No. 629,767,
and in Germany September 24, 1931

4 Claims. (Cl. 80—35)

My invention relates to continuous wire mills in which the wire is finished in a continuous operation. The first rolling mills of this kind consisted of several groups of housings, in which the last one, i. e. the finishing group was driven by means of a complicated belt drive. The wire thus produced has mostly a diameter of about five (5) millimeters. The initial material from which this wire is rolled, usually are bars, fifty (50) millimeters square. These initial and final cross-sections determine on the basis of the continuous rolling principle the number of housings, while the output to be obtained is determined by the speed at which the wire leaves the finishing rolls. Because of the small weight per meter of wire having a diameter of five (5) millimeters, the speed with which the wire leaves the finishing rolls, must be very high so as to obtain an economical production. But it was found again and again that as regards the speed at the finishing rolls there are limits, due to practically insurmountable difficulties.

In order to reach an output insuring to some extent the profitable operation of such a plant one proposed to so design the housing of the finishing rolls that two wires would leave said rolls instead of one wire, whereby the output, if not doubled, was at least considerably increased. This, however, also continually involved unexpected difficulties which it was hard to overcome and the causes of which largely remained unexplained. One of the most pronounced drawbacks was the impossibility to produce clean, round wire of uniform diameter, since the two passes in each group of finishing rolls could not be maintained in accurate relative adjustment, as is necessary for the production of a faultless rolled product.

Later on, the group of finishing rolls, through which two parallel wires were passed, was subdivided into two independent groups of housings arranged parallel to each other, and in each of these housings only one wire was rolled. By this expedient, one had hoped to be able to so adjust the passes of the housing relative to each other that the finished product would in a better way fulfill the requirements as regards shape and uniform diameter. But again and again, it was found that also by this last mentioned arrangement the said object could not be attained, aside from the fact that because of the increased cost of the plant, the need of increasing the output became greater in order to insure the profitable operation of the plant. This in turn made it

necessary to considerably increase the speed of the wire leaving the finishing rolls.

Also this expedient involved certain insurmountable difficulties, because with the increase in the speed the tuning of the passes and their speed became much more difficult, entirely aside from the fact that the great increase in speed also entailed certain drawbacks in the operation of the plant, especially as regards accidents.

Thereupon, one attempted to operate the last housings of finishing rolls no longer by means of gears or belt drive, but to equip each housing of the two parallel groups of finishing rolls with a separate motor, which experiment, however, was a complete failure, because also in this instance the difficulties of regulating the speed, especially of the last fast running finishing rolls, could not be overcome, which difficulties it had been impossible to foresee.

Now, the object of the present invention is to so arrange the housings and to provide such a drive as to thereby completely eliminate the above noted difficulties and drawbacks as regards the relative adjustability of the various housings in respect of speed and the tuning of the successive passes. I have discovered that the above difficulties can be overcome, if the rotating masses of the several housings to be regulated are brought into such a proportion to the various speeds that the regulation and tuning of the housings relative to each other can be effected practically without stages, as is absolutely required by a continuous rolling operation. The present invention is based on the discovery that the speed of the wire as it leaves the finishing rolls must not be increased but rather decreased, and must be maintained within such limits as to fully insure a practical control of each single speed, and to facilitate this object by a considerable reduction of the rotating masses to be controlled as compared with the designs heretofore used.

In order to insure economical operation by way of a sufficiently large output, the plant, in accordance with this invention, is so designed that not only two but more than two wires simultaneously pass parallel to each other through independent sets of finishing rolls. Obviously, with such an increase of parallel wires, the speed of the finishing rolls can be so much decreased as to insure a profitable output.

On the annexed drawing, there is shown in Fig. 1 diagrammatically a wire rolling mill embodying the invention; Fig. 2 is a detail view of a generator set used for driving the separate motors.

The successive groups of housings indicated on the drawing at 1, 2 and 3 respectively represent the housings containing the rough and intermediate rolls. At 4, 5 and 6 are indicated the parallel groups of housings containing the finishing rolls. In accordance with this invention, the rotating masses of the finishing groups are reduced. In order to enable this object to be obtained, each individual roll of the groups of finishing rolls is conveniently equipped with a direct electric driving motor, the rotor element of which, because of a special design of the motor, has the smallest possible dimensions.

Due to this expedient of reducing the rotating masses, a means is afforded to so relatively tune, without stages, the speed of the various rolls in but a very small fraction of a second (about one hundredth of a second) as is absolutely required by a smooth continuous rolling operation. On the drawing, there are indicated at 7, 8 and 9 the electric motors for driving the rolls of the first three groups of housings 1, 2 and 3.

The parallel disposed groups of the sets of finishing rolls, indicated at 4, 5 and 6 are shown on the drawing as being equipped with an individual driving motor 10 and 11 respectively for each finishing roll. My invention, however, is not limited to this arrangement, because instead of each roll having its individual driving motor, each pair of rolls can be driven by a common motor, provided only that the above said condition of the rotating masses being reduced to a minimum is fulfilled, in accordance with the present invention. Current may be supplied to the various motors, 7, 8, 9, 10 and 11 by a so-called Leonard generating set shown at 12 in Fig. 2, which has a special generator for each group of housings.

While I have shown and described an embodiment of my invention, I have done so by way of illustration, and my invention, therefore, is not limited thereto.

I claim as my invention:

1. In a continuous wire mill, the combination with a plurality of successively disposed groups of primary and intermediate housings designed to deliver more than two pre-rolled bars, of more than two groups of finishing housings dis-

posed parallel with each other, each of said last-named groups being arranged to receive from said group of intermediate housings but one bar for final rolling.

2. In a continuous wire mill, the combination with a plurality of successively arranged groups of primary and intermediate housings designed to deliver more than two pre-rolled bars, of more than two groups of finishing housings disposed parallel with each other, each of said last-named groups receiving but one bar for final rolling, a driving motor for operating each of said groups of primary and intermediate housings, and a separate driving motor for each finishing roll of said groups of finishing housings. 80

3. In a continuous wire mill, the combination with a plurality of successively arranged groups of primary and intermediate housings designed to deliver more than two pre-rolled bars, of more than two groups of finishing housings disposed parallel with each other, each of said last-named groups receiving but one bar from said group of intermediate rolls for final rolling, a driving motor for operating each group of said primary and intermediate housings, and a driving motor for directly operating each finishing roll of said groups of finishing housings, said last named driving motors being capable of speed-control relative to the said first mentioned driving motors. 95

4. In a continuous wire mill, the combination with a plurality of successively arranged groups of primary and intermediate housings designed to deliver more than two pre-rolled bars, of more than two groups of finishing housings disposed parallel with each other, each of said last-named groups receiving but one bar from said group of intermediate rolls for final rolling, an electric motor for operating each group of said primary and intermediate housings, and a separate electric motor for operating each finishing roll of said groups of finishing rolls, the rotating masses of said electric motors and the finishing rolls operated thereby being so small as to make them instantly respond to any impulse for controlling the desired speed. 110
